THEODOR KORTHÄUER, OF BERLIN-SIEMENSSTADT, GERMANY, ASSIGNEE, BY MESNE ASSIGNMENTS, TO AMERICAN TELEPHONE AND TELEGRAPH COMPANY, A CORPORATION OF NEW YORK

TELEPHONE SYSTEM

Application filed October 23, 1929, Serial No. 401,849, and in Germany May 16, 1928.

This invention relates to electric telephone systems and is more particularly concerned with such systems, automatic in character, in which one idle line of a number of available connecting lines is automatically selected, upon the initiation of a call by a subscriber. The main object of this invention consists in enabling the determination of the particular line selected, by an automatic selecting device.

In many cases, it is desirable, or required, for specific reasons, to determine which one of a plurality or a group of connecting lines, across which connection is made from a calling subscriber to a called subscriber, has been selected. For example, this is the case in systems where a connection from a calling to a called subscriber is made partly manually by an operator and partly automatically by means of a switching mechanism. If, in such a case, there exists a specific regulation of rates for telephone conversations, it is necessary for the operator to know which one of a group of available connecting lines has been picked out by an automatic selector switch, in order to enable her to check up the completion of a desired call. For instance, this is the case where existing local automatic exchanges may be connected with each other by a distant exchange served by an operator.

In accordance with this invention, it is made possible to indicate the seizure of a connecting line, picked out from a group of available connecting lines, in that definite simple signals are provided, showing the specific line selected for the connection. In accordance with the preferred embodiment of the invention, a switching mechanism is operated upon initiation of a call by a calling subscriber, after seizure of an idle line, selected from a group of available connecting lines. This switching mechanism is operated in such a manner that the calling subscriber, or the operator at the exchange, readily recognizes the specific line selected.

The invention will become more clear as the following detailed description proceeds, which is taken in conjunction with the accompanying drawings, which are chosen as

illustrative examples of the fundamental inventive idea and which, it should be understood, are, by no means, intended to have the effect of limiting the interpretation of the invention, short of its broad and most comprehensive scope, as expressed in the appended claims.

Figure 1 shows a circuit diagram of an automatic telephone system, in which the idea of my invention is embodied. Figure 2 is a similar diagram, for obtaining the same object in a modified manner. Similar reference characters refer to similar elements in both figures of the drawing.

In the diagrams of the drawings, relay windings and contacts operated by the same, are designated by co-ordinate characters, the windings being marked by capital characters and the corresponding contacts by small characters. The terms "resting contact" and "working contact" are used in the following description, the former meaning the condition of a relay contact in its de-energized condition and the latter meaning the condition of a relay contact in its energized condition.

According to both examples shown by the two figures of the drawings, an idle connecting line is picked out, by means of a pre-selector switch, (also called line switch) from an available group of identical such connecting lines, upon initiation of a call by a calling subscriber.

Referring more particularly to Figure 1, with the initiation of a call by a subscriber T_n , such as, for instance, by lifting his receiver, the circuit loop of the subscriber will be closed and the relay R of the pre-selector, or line switch, $V. W.$ becomes energized. The circuit of this relay is traced as follows: Ground, operating battery, winding I of relay R , resting contact $1t$, connecting line $a1$, subscriber loop T_n , connecting line $b1$, resting contact $2t$, winding II of relay R , back to ground.

Thus, relay R is energized and connects, by operation of its associated contacts, the following circuits of the pre-selector $V. W.$: Ground, interrupter U , winding D of rotary operating magnet, resting contact $3t$, work-

ing contact $4r$ —which has been operated because of the energization of the relay R upon initiation of the subscriber's call—contact O , switch arm 5 , battery, back to ground.

5 The pre-selector $V. W.$ is advanced by one step and, accordingly, the following circuit for the rotary magnet D is established: Ground, interrupter U , winding of rotary magnet D , resting contact $3t$, contact bank 10 1—10, switch arm 5 , battery, back to ground.

The rotary magnet D will further advance the pre-selector $V. W.$, until it reaches an idle line from the group of available connecting lines. Assuming that such idle line has been 15 found, the following circuit will be established: Ground, battery, contact arm 5 , contact bank 1—10, working contact $4r$, windings II and I of relay T , test line $c1$, switch arm C of pre-selector $V. W.$, windings I and 20 II of relay C , back to ground.

By the establishment of this circuit, relays T and C will be energized. Contacts $1t$, $2t$ and $3t$, associated with the relay T , will, accordingly, be operated. By such operation 25 of contacts $1t$ and $2t$, the subscribing station Tn will be connected with the idle line selected by the pre-selector from the group of connecting lines. The circuit for the relay R will, accordingly, be interrupted and the 30 relay become de-energized. Furthermore, the relay C is energized by the establishment of the above mentioned circuit and will open its contact $5c$, thus inserting winding of the relay C , which has a high ohmic resistance, 35 into the circuit of the relays C and T . By the operation of the contact $3t$, associated with the relay T , the winding II of the relay T will be disconnected from the above described 40 circuit. The circuit for the relays C and T will then be as follows: Ground, battery, contact arm 5 , contact bank 1—10, working contact $3t$, winding I of relay T , test line $c1$, switch arm c of pre-selector $V. W.$, windings 45 I and II of relay C , back to ground. In accordance with this invention, the pre-selector $V. W.$ is provided with a fourth contact bank, besides the usual three contact banks, two of 50 which (switch arms a and b) serve for the connection of the two operating lines ($a1$ and $b1$) and the third of which (switch arm c) serves for control and test purposes.

Resistances Wi , of different values, are inserted in the connections to the contacts of the fourth contact bank, the different resistance values corresponding to the individual connecting lines. An ammeter M is arranged 55 at the subscriber station, or also at the exchange, to be observed by the subscriber, or by the operator. Whenever an idle line of the available group of connecting lines is seized by the pre-selector $V. W.$, a current circuit for the ammeter M will be closed, which includes a resistance co-ordinated to the specific line which has been selected. The 60 trace of the current, in accordance with Fig-

ure 1 for this circuit, is as follows: Ground, to battery, resistance Wi , switch arm d , line $d1$, ammeter M , back to ground.

The ammeter will show a definite deviation, depending on the value of the resistance Wi , in accordance with the individual line of the available group of connecting lines picked out by the pre-selector $V. W.$ The calling subscriber, or the operator, may, thus, easily and immediately observe over which 70 line of the connecting lines the connection has been made. In case the ammeter is arranged at the subscriber station, the subscriber may apprise the operator of the specific line selected by the pre-selector, or, in case the ammeter M is arranged at the operator's end, the operator, herself, may observe which of the connecting lines has been picked out. The ammeter will be energized during the 75 entire period of conversation and, thus, apprise the operator, or any other control person, at all times, of the real trace of the connection from the calling subscriber to the called subscriber and, thus, enable her to enter into the connection and control the final 80 completion of a desired call. The calibration of the ammeter scale may be made such that it directly indicates the number, or any other marking of the line which has been selected. 85

Whenever the calling subscriber Tn is connected to an idle line of the group of available connecting lines, he may proceed to make his call, for instance, by transmitting a definite number of current impulses, by 90 means of his dialing device, or he may have the operator make the connection manually. The relay J , across which the calling subscriber receives its supply current, will then be energized through the following circuit: 95 Ground, battery, winding I of relay J , switch arm a of the pre-selector $V. W.$, working contact $1t$, connecting line $a1$, subscriber station Tn , connecting line $b1$, working contact $2t$, switch arm b , winding II of relay J , back to 100 ground. 105

With the energization of relay J , contacts $8j$, $9j$ and $6j$ will be operated. By the closing of the contact $8j$, a circuit is formed for a further relay V from ground to battery, the winding of relay V working contact $8j$ 110 back to ground. With the transmission of the selecting current impulses by the calling subscriber, the current impulses will be transferred by means of the relay J and the current impulse contact $6j$ to the impulse current receiver. Thus, with the first release of the armature of relay J , the following circuit is formed for a further relay N : 115 Ground, battery, winding of relay N , resting contact $9j$, working contact $10v$, back to ground. 120

During the period of impulse transmission, the relay V which is a relay with delayed action and, similarly, the relay N remain energized. Thus, the contact $7n$, asso- 125 130

ciated with the relay N, will short circuit a choke coil Dr during the impulse transmission period, whereby a better transmission of the current impulses is secured. Further details about the completion of the connection will not be discussed, because they are not essential for an understanding of the novel feature of the present invention.

Furthermore, no description will be given of the final completion of the call, as this, also, has no bearing on the operation of the new additional device provided in accordance with the invention.

Referring to the circuit diagram of Figure 2, which represents a modified system of that shown by Figure 1, means are provided for indicating acoustically the specific line of a group of available connecting lines, selected upon initiation of a call by a calling subscriber Tn1, instead of operating an optical signal, such as provided in accordance with the exemplification of the invention, illustrated by Figure 1. The subscriber Tn1, upon the initiation of a call, is connected in the same manner as in Figure 1, with an idle line of an available group of connecting lines, by means of an automatic pre-selector, or line switch, as described. The operation of this pre-selector will not be discussed, as this has been done with reference to Figure 1. Assuming that the calling subscriber Tn1 is connected with an idle line of the group of available connecting lines, the following circuit for the relay J1 will be formed: Ground, to battery, winding I of the relay J1, switch arm a1 of the pre-selector V. W. 1, connecting line a2, working contact 1s1, subscriber station Tn1, working contact 2s1, connecting line b2, switch arm b1, winding II of relay J1, back to ground.

The relay J1 will be energized by this circuit and, by operation of its contact 8j1, will close a circuit for the relay V1, which circuit is traced from ground to battery to winding of the relay V1, working contact 8j1, back to ground. Thus, the relay V1 responds and operates contacts 10v1, 13v1 and 14v1. By the closing of the contact 14v1, a buzzer U2 is inserted in the line b2 of the subscriber's line. Thus, the calling subscriber Tn1 will receive a distinct signal, which will notify him over which of the available connecting lines he has been connected. A buzzer is co-ordinated to each one of the lines of the group, whereby different announcements will be given to the subscriber. With the transmission of the calling current impulses of the subscriber Tn1, the relay J1 transfers the current impulses sent out by the subscriber across the current impulse contact to the subsequent current impulse receiver. With the first release of the relay J1 during the transmission of the current impulses, the following circuit will be formed for the relay N1: ground, to bat-

tery, winding of relay N1, resting contact 9j1, working contact 10v1, back to ground.

The relay V1 remains energized during the entire period of the current impulse transmission, for which purpose it is designed, as a relay with delayed action and so is the relay N1. Through the response of the latter relay N1, the contact 11n1 is closed, forming the following circuit for the relay H: Ground, to battery, winding of relay H, working contact 11n1, working contact 13v1, back to ground.

The relay H is energized by this circuit and maintains itself in an energized condition, by means of its own holding current circuit, closed over contact 12h. By opening of the contact 15h, operated by the relay winding H, the buzzer U2 is disconnected. The relay H remains energized during the entire period of the connection and, similarly, the relay V1, whereas the relay N1 becomes de-energized after the completion of the impulse current transmission. During the transmission of the impulse currents, the choke coil Dr1 is short-circuited by means of contact 7n1, in order to improve the operation of the impulse transmission.

The further operations necessary for completing a call and dissolving the same, after termination of a conversation, will not be described, as they have no reference to the object of the present invention.

While I have described my invention, more or less specifically, with reference to the showing herein, it is obvious that I would have it understood that my invention may be practiced in many other ways, without departing from the spirit and scope thereof, in attaining the objects, as hereinbefore set forth.

What I claim to be secured by Letters Patent in the United States is:—

1. In a telephone system, an automatic switch having brushes and contacts, a telephone line terminating in brushes of said switch, a group of trunks appearing in the contacts of said switch, means responsive to the initiation of a call at the substation of said line for setting said automatic switch in motion to select an idle trunk and to extend said line thereto, distinguishing elements, each individual to a different one of said trunks, means for connecting said elements through the brushes of said switch to said line, and signal means responsively controlled by said distinguishing elements for identifying the particular trunk to which said line is connected.

2. In a telephone system, an automatic switch having brushes and contacts, a telephone line terminating in the brushes of said switch, a group of trunk circuits appearing in the contacts of said switch, means controlled over said line for setting said switch in operation to select an idle trunk and to extend said line thereto, resistance elements,

each individual to one of said trunks, said elements differing from each other in order to distinguish said trunks, and an indicating meter connected to a brush of said switch and included in circuit with said resistance elements to give a visual indication identifying the particular trunk to which said line is connected.

3. In a telephone system, an automatic switch having brushes and contacts, a telephone line terminating in the brushes of said switch, a group of trunks appearing in the contacts of said switch, means responsive to the initiation of a call at the substation of said line for setting said automatic switch in motion to select an idle trunk and to extend the line thereto, tone producing devices, each differing from the other and respectively individual to said trunks, means for connecting said tone devices through the brushes of said switch to said telephone line, and means at the substation responsive to said tone producing devices for giving a signal identifying the particular trunk to which said line is connected.

In testimony whereof I affix my signature.

THEODOR KORTHÄUER.
